(57) **CLAIM**

The ornamental design for a fountain planter, as shown and described.

DESCRIPTION

FIG. 1 is a front elevational view of a fountain planter;

FIG. 2 is a rear elevational view thereof;

FIG. 3 is a left side elevational view thereof;

FIG. 4 is a right side elevational view thereof; and,

FIG. 5 is a top plan view thereof, shown in an alternate position of use.

The bottom of the fountain planter is flat and unornamented.
